US00D704447S

(12) **United States Design Patent**
Xi et al.

(10) **Patent No.:** **US D704,447 S**
(45) **Date of Patent:** ** *May 13, 2014

(54) **TOOTHBRUSH**

(71) Applicant: **Colgate-Palmolive Company**, New York, NY (US)

(72) Inventors: **Wen Jin Xi**, Shanghai (CN); **Guang Sheng Guo**, Yangshou (CN); **Bo Zhang**, Yangshou (CN); **Li Ping Zhang**, Yangshou (CN)

(73) Assignee: **Colgate-Palmolive Company**, New York, NY (US)

(*) Notice: This patent is subject to a terminal disclaimer.

(**) Term: **14 Years**

(21) Appl. No.: **29/451,267**

(22) Filed: **Mar. 29, 2013**

(51) **LOC (10) Cl.** **04-02**

(52) **U.S. Cl.** **D4/104**
USPC **D4/104**

(58) **Field of Classification Search**
USPC D4/101, 104–112, 132–134, 138;
15/143.1, 167.1, 167.2; 16/430;
132/308–311; 601/139, 141

See application file for complete search history.
